UNITED STATES PATENT OFFICE.

CLARK ORR, OF FORT WAYNE, INDIANA, ASSIGNOR TO GENERAL ELECTRIC COMPANY,
A CORPORATION OF NEW YORK.

ROTARY REFRIGERATING-MACHINE.

1,326,686.

Specification of Letters Patent. Patented Dec. 30, 1919.

Application filed February 24, 1919. Serial No. 273,816.

To all whom it may concern:

Be it known that I, CLARK ORR, a citizen of the United States, residing at Fort Wayne, in the county of Allen, State of Indiana, have invented certain new and useful Improvements in Rotary Refrigerating-Machines, of which the following is a specification.

My invention relates to rotary refrigerating machines of the type in which a suitable material, such as sulfur-dioxide in the form of a saturated or approximately saturated vapor or gas, is confined in a hermetically sealed container, comprising a compressor or condenser portion and a refrigerator portion. In such machines, the sulfur-dioxide, or other suitable refrigerant, is acted upon mechanically in the compressor or condenser portion of the container to cause it to liquefy and lose potential energy in the form of heat which is transmitted to and dissipated by a medium outside that portion of the container; the material within the condenser portion being then conveyed to the refrigerator portion where it vaporizes and effects the refrigeration of a medium surrounding that portion of the container by absorbing heat therefrom. Besides the sulfur-dioxide or similar refrigerant, the container also has a lubricant therein for lubricating the working parts of the refrigerating machine. Such a machine is described in the U. S. patent to Andiffren and Singrün No. 1,155,780, dated October 5, 1915, and the U. S. patent to J. J. Wood No. 1,164,245, dated December 14, 1915.

In such machines, it is impracticable to get complete separation of the lubricant and liquid refrigerant in the condenser portion of the machine, with the result that the liquid refrigerant passing from the condenser portion of the machine to the refrigerator portion carries with it some lubricant which must be returned to the condenser portion. In order to accomplish this, the refrigerator portion of the machine is provided with a liquid and lubricant separator arranged to collect the lubricant and refrigerant, separate them, re-deliver the refrigerant to the surface of the container to be vaporized, and deliver the lubricant to the working parts of the machine.

It is the object of my invention to provide an improved liquid and lubricant separator, which is of simple and cheap con-

struction containing fewer parts than those heretofore used.

For a full and complete understanding of the novel features of construction of my invention, reference may be had to the following description taken in connection with the accompanying drawing, in which Figure 1 is a sectional view through the refrigerator portion of the container of a refrigerating machine, showing the separator of my invention partly in cross section, and Fig. 2 is a side view, partly in cross section, of the separator removed from the container.

Referring to the drawing, 1 is the refrigerator portion of the hermetically sealed container of the refrigerating machine which is connected by a hollow shaft 2 to the condenser portion of the machine.

Projecting through the hollow shaft 2 into the portion 1 of the container, is a hollow stationary tube 3 which serves to convey the refrigerating liquid from the condenser to the refrigerator portion. On this stationary tube 3 is mounted my separator which comprises a central member 4, a U-shaped member, consisting of two U-shaped tubes 9 and 12, fastened to the member 4 and having one end communicating with the interior thereof, and a collector 14 mounted on the other end of the U-shaped member 80 extending into proximity with the periphery of the container for conveying liquid from adjacent the periphery of the container to said U-shaped member. The central member 4 is shown as a rectangular 85 box provided at one side with a clamping portion 5 by which it is attached to the stationary hollow tube 3, and at the opposite side with a projecting hub 6 by which it is loosely journaled on the shaft 2.

The bottom of the central member 4 is solid and its two sides are shaped to receive the two ends respectively of the U-shaped tube 9 which is riveted or otherwise permanently attached thereto as best shown in Fig. 10. Between one of these sides of the central member 4 and the adjacent leg of the U-shaped tube 9 is provided a communicating passage 10. In the other leg of U-shaped tube 9 and somewhat above its mid-height 10 is an opening in which is fastened an overflow pipe 11 extending to a point near the side wall of the container.

Within the U-shaped tube 9 is located the second U-shaped tube 12, of relatively small 11

diameter. One end 15 of the U-shaped tube 12 extends well above the end of the outer U-shaped tube 9, and the other end 16 of the tube 12 terminates below the point where the tube 9 communicates with the central member 4. The long leg of inner tube 12 is located in the leg of tube 9 which is provided with the overflow pipe 11. In order to facilitate the assembly of the U-shaped member consisting of the tubes 9 and 12, the outer tube 9 is split at 13. In assembling, the tube 12 is first placed in the bent portion of the tube 9. After the tube 12 is put in place in this portion of tube 9, the straight section of the leg of tube 9 above the split 13 is placed in position and welded or otherwise attached to the bent portion of tube 9 at the joint 13.

On the end of the U-shaped tube 12 which extends beyond the tube 9 is fastened a projecting fin-shaped liquid collector 14 which extends into close proximity to the periphery of the container. This liquid collector 14 is shown as being constructed in accordance with my Patent No. 1,281,821, dated October 15, 1918.

The top of the central member 4 is provided with an opening 7 and a surrounding lug 17. On this lug 17 is fitted one end of a bent tube 8. It is shown as being mounted in a plane at right angles to the member 9.

The operation of my separator is as follows:—The collector 14 dips into the film 35 of lubricant and refrigerant and carries the proper amount down into the tube 12 of the U-shaped member. The mixture of the lubricant and liquid refrigerant carried into the tube 12 flows out of the end 16 thereof and the refrigerant, being the heavier, drops to the bottom of the outer U-shaped tube 9. As it rises above the bend in this tube, it causes the lighter lubricant to rise only in the right-hand leg of tube 9 45 (Fig. 2); the refrigerant settling in the curve and rising in both legs of tube 9. When the lubricant rises in the right-hand leg of tube 9 to the level of the shaft, it flows through the passage 10 into the central member 4 from which it is sucked back 50 into the compressor portion of the machine through the hollow shaft 2. The liquid refrigerant rises in the left-hand leg of tube 9 and flows out through the overflow pipe 11 and is discharged against the wall of container 1 well up toward the shaft 2. The height at which the overflow pipe 11 is placed in the tube 9 is determined by the difference in specific gravity of the lubricant and liquid refrigerant. This height is 55 made such that a sufficient amount of liquid refrigerant is trapped in the U-shaped tube 9 to raise the level of the lubricant to such a height that it will flow into the opening 60 10. Any additional liquid refrigerant

trapped in the U-shaped tube 9 will flow out of the overflow pipe 11.

The evaporated refrigerant is sucked through the bent tube 8 into the central member 4 and drawn through the hollow 70 shaft 2 into the condenser portion of the container.

In separators previously built, the port for admitting the vaporized refrigerant to the hollow shaft has been located so that it 75 is in line with the splash from the oil separator, resulting in a moist gas being sucked back into the compressor cylinders. In my improved separator, however, the free end of the tube 8 is so located that this is prevented; and any moisture that may be drawn into the tube is deposited on the wall of the free leg of this tube 8 and drops back into the refrigerator chamber, so the vapor which enters the shaft is comparatively dry. 80

I desire it to be understood that my invention is not limited to the particular form or arrangement of parts shown and described herein, and I aim in the appended claims to cover all modifications which do 90 not depart from the spirit and scope of my invention.

What I claim as new and desire to secure by Letters Patent of the United States, is:—

1. In a refrigerating machine, the combination with a rotatable container, of a separator therein comprising a central member, a U-shaped member fastened to said central member and having one end communicating with the interior thereof, a collector mounted on the other end of said U-shaped member for conveying liquid from adjacent the periphery of said container to said U-shaped member, and an overflow pipe mounted in the side of said U-shaped member. 100

2. In a refrigerating machine, the combination with a rotatable container, of a separator therein comprising a central member, a U-shaped member fastened to said central member and having one end communicating with the interior thereof, a collector mounted on the other end of said U-shaped member for conveying liquid from adjacent the periphery of said container to 115 said U-shaped member, and an overflow pipe mounted in the side of said U-shaped member below said central member but at such a height that a sufficient amount of liquid refrigerant is trapped in said U-shaped member to raise the level of the lubricant so that it will flow out of the end of said U-shaped member communicating with the interior of said central member. 120

3. In a refrigerating machine, the combination with a rotatable container, of a separator therein comprising a central member, a U-shaped member fastened to said central member and having one end communicating with the interior thereof, a col- 125

- lector mounted on the other end of said U-shaped member for conveying liquid from adjacent the periphery of said container to said U-shaped member, an overflow pipe 5 mounted in the side of said U-shaped member below said central member but at such a height that a sufficient amount of liquid refrigerant is trapped in said U-shaped member to raise the level of the lubricant 10 so that it will flow out of the end of said U-shaped member communicating with the interior of said central member, and a bent tube mounted on the top of said central member and communicating with the interior thereof for admitting gas thereto.
4. In a refrigerating machine, the combination with a rotatable container, of a separator therein comprising a central member, a U-shaped member fastened to said central member and having one end communicating with the interior thereof, a second U-shaped member contained within said first mentioned U-shaped member, having one end extending above the other end of said first mentioned U-shaped member, and having its other end terminating below the point where said first mentioned U-shaped member communicates with said central member, and a collector mounted on the end of said second 25 U-shaped member which extends above the end of said first mentioned U-shaped member for conveying liquid from adjacent the periphery of said container to said second U-shaped member.
5. In a refrigerating machine, the combination with a rotatable container, of a separator therein comprising a central member, a U-shaped member fastened to said central member and having one end communicating with the interior thereof, a second U-shaped member contained within said first mentioned U-shaped member, having one end extending above the other end of said first mentioned U-shaped member, and the other end terminating below the level of said overflow pipe, a collector mounted on the end of said U-shaped member which extends above the end of said first mentioned U-shaped member for conveying liquid from adjacent 30 the periphery of said container to said second U-shaped member, an overflow pipe mounted in the side of said first mentioned U-shaped member below said central member but at such a height that a sufficient amount of liquid refrigerant is trapped therein to raise the level of the lubricant 35 so that it will flow out of the end of said first mentioned U-shaped member communicating with the interior of said central member.
6. In a refrigerating machine, the combination with a rotatable container, of a separator therein comprising a central member, a U-shaped member fastened to said central member and having one end communicating with the interior thereof, and a second U-shaped member contained within said first mentioned U-shaped member, having one end extending above the end of said first mentioned U-shaped member, and the other end terminating below the level of said overflow pipe, a collector mounted on the end of said U-shaped member which extends above the end of said first mentioned U-shaped member for conveying liquid from adjacent 40 the periphery of said container to said second U-shaped member, an overflow pipe mounted in the side of said first mentioned U-shaped member below said central member but at such a height that a sufficient amount of liquid refrigerant is trapped therein to raise the level of the lubricant 45 so that it will flow out of the end of said first mentioned U-shaped member communicating with the interior of said central member, and a bent tube mounted on the top of said central member and communicating with the interior thereof for admitting gas thereto.

In witness whereof, I have hereunto set my hand this 17th day of February, 1919. 90

CLARK ORR.
